[57] CLAIM

The ornamental design for a motorized golf bag carrier,
as shown.

DESCRIPTION

FIG. 1 is a side elevational view of a motorized golf
club bag carrier showing my new design;

FIG. 2 is a front elevational view thereof;

FIG. 3 is a side elevational view thereof opposite to that
shown in FIG. 1 in collapsed condition;

FIG. 4 is a rear elevational view thereof;

FIG. 5 is a bottom plan view thereof; and

FIG. 6 is a top plan view thereof.
